UNITED STATES PATENT OFFICE.

WILLIAM V. HEINZ, OF LA SALLE, ILLINOIS.

COAL-CHUTE.

1,286,618.

Specification of Letters Patent.

Patented Dec. 3, 1918.

Application filed January 25, 1917. Serial No. 144,387.

To all whom it may concern:

Be it known that I, WILLIAM V. HEINZ, a citizen of the United States, residing at La Salle, in the county of La Salle, State of Illinois, have invented certain new and useful Improvements in Coal-Chutes, of which the following is a specification.

My invention relates to chutes used for conducting coal and the like through a window into storage space and particularly to a chute having a door preferably glazed, and adapted to close the end of the chute and a hopper movably mounted in the chute and automatically moved by the door.

One of the objects of my invention is to provide a chute mounted in the wall of the building having a metal door or closure provided with a transparent section of glass, mica or the like for the admitting of light to the interior of the building to which the chute is applied.

A further object is to provide a hopper slidably mounted in the mouth of the chute and connected by suitable means to the door so that when the door is opened the hopper will be drawn out and form an extension to the chute.

A still further object is to provide a protecting plate to prevent the glazed section of the door from being broken by material delivered through the chute.

A further object is to associate with such protecting plate for the glazed section means whereby the plate may be allowed to drop into the lower portion of the hopper when the door is in closed position, thereby offering no hindrance to the passage of light through the glass to the interior of the cellar or basement and whereby the plate is automatically moved into protecting relation to the glass when the chute is in use.

I am aware that coal chutes having a hopper mounted therein and having metal doors or closures are known. The disadvantages of such known constructions are that the opening or closing of the door and the movement of the hopper are independent and that such means is required to hold the door in opened position, also to hold the hopper in outward position. These objections are overcome in the chute of my invention.

In order to enable those skilled in the art to more fully understand my invention attention is directed to the drawings wherein:

Figure 1 is a vertical section through a

wall of a building showing the construction of the coal chute embodying my invention the same being shown with the door in closed position.

Fig. 2 is a similar view the parts being shown with the door in opened position.

Fig. 3 is a front elevation showing the door in raised position.

Fig. 4 is a front view showing the door in closed position.

Fig. 5 is a fragmentary view of the hopper in outward position showing the stops for maintaining the hopper in outward position.

Fig. 6 is a view similar to Fig. 1 showing a modification in the means of unlocking the door from inside the building.

Fig. 7 is the same as Fig. 6 with door in opened position.

10 indicates a wall of a building having an opening 11 containing a chute 12 preferably with a downwardly sloping bottom portion 13. A frame 14 surrounds the opening 11 at the outer end of the chute 12 and to it is hinged a door frame 15 by pintles 16 and 17. In the door 15 is a glass or other transparent member 18. Mounted within and lying along the inclined bottom 13 of the chute 12 is a hopper 19 adapted to be inclosed wholly within the chute when the door is in closed position and to extend outwardly therefrom when the door is in opened position. This hopper comprises a bottom member 20 and side walls 21 and is open at the top. For moving the hopper 19 I employ link arms 22 pivoted at 23 to the hopper and at 24 to the door. On the free edges and on opposite sides of the door are perforated lugs 25 to which is pivoted a protecting plate 26 adapted to assume a substantially horizontal position in the bottom of the hopper when the door is closed as best seen in Fig. 1 and to overlie the glass 18 in the door 15 when the door is in opened position as best seen in Fig. 2. To aid in the holding of the plate 26 in front of the glass 18 I attach a chain or other flexible means 27 to the protecting plate 26 fastening the inner end of the chain to the upper portion of the chute 12 at 28.

I prefer to hold the door in opened position by providing suitable stops against which the rear end of the hopper abuts and thus is retained in outward position and consequently holds the door open by virtue of the link connections therebetween.

105
110

These stops serve also as guiding means to prevent sidewise play of the hopper as it is moved back and forth by the operation of the door. They also serve as means for 5 guiding the hopper in its rearward travel as it is moved from opened position.

Frame 14 has a flange 29, the opening formed thereby being greater in vertical dimension than the vertical height of the 10 hopper 19 and in length only slightly more than the width of the hopper. Secured to the rearward edges of the side walls 21 of the hopper are angle bar stops 30 which terminate short of the bottom of the hopper 19 as best seen in Fig. 5. When the door is raised and the hopper 19 withdrawn to its outer position these stops 30 will abut the inner faces of the flange 29, thus preventing any further outward movement of the hopper 19. At the outer end of the chute and positioned so as to clear the side walls of the hopper are stops 31 as shown in Fig. 5, the height of these stops being such as to contact the stops 30 when the hopper is 20 pulled to its outward position. It will be seen by this arrangement that as the hopper is pulled outwardly it will ride up over the stops 31 because of the contact therewith of the stops 30 and after clearing the tops 25 thereof fall down in front of them and thus prevent any further rearward movement of the hopper. Also the stops 30 abut the flange 29 on the door frame 14 and thus prevent any outward travel of the hopper or 30 any tendency to fall outwardly. The links 22 connecting the door and the hopper are so positioned that the door will be held in opened position as long as the rear edge of the hopper is in contact with the stops 31 and the stops 30 abut the flange 29.

For locking the door 15 when it is closed I provide a hook latch 32 on the lower portion thereof which engages a catch 33 incorporated in the lower portion of the frame 45 14 as indicated in Fig. 1. When in closed position the parts are disposed as in Fig. 1 with the latch 32 engaging the catch 33 and the latch 32 can not be disengaged except from the inside of the building. When the 50 latch 32 is disengaged the door may be raised thus drawing out the hopper 19. The raising movement of the door is continued until the hopper travels over the stops 31 and the stops 30 engage the flange 29 on 55 the inside and the stops 31 on the outside, thus holding the hopper in outward position and the door in opened position. As the door 15 is raised to an open position plate 26 will move from the position shown in 60 Fig. 1 to the position shown in Fig. 2 and overlie the glass 18 in the door 15. If, for any reason, the plate 26 does not move freely the chain 27 will draw it inwardly thus insuring protection to the glass 18.

65 In the modification shown in Figs. 6 and

7 a novel means of unlatching the door from the inside of the building is disclosed. In Figs. 6 and 7 the latch 34 has an enlarged end 34^a provided with an eye. Connecting the eye with the plate 26 is a flexible connection 35 the purpose of which will be explained later. At the lower end of the plate 26 secured thereto is an offset member 36. Fastened to this member 36 is a flexible member 37 passing through a ring or other device 38 fastened to the upper portion of the chute 12. At the end of the member 37 there is provided a ring or other means larger than the opening in the member 38. This ring is designated by 39. The 80 function of the member 37 of Figs. 6 and 7 is the same as that of the member 27 in Figs. 1 and 2, that is to draw the protector plate against the glass in the door when the door is in opened position. The modification 85 shown affords a means for unlatching the door from inside the building without having to enter the basement where the chute is in position. While the member 37 is shown as terminating beyond the member 38, nevertheless, this may be lengthened in any desired manner so as to be operated from a distance. As the hinges 16 of the door are so arranged that the pivotal members thereof are outwardly of the point of engagement 90 between the latch 34 and the catch 33, it will be seen that when the latch is disengaged the door will be swung outwardly a short distance; hence, when it is desired to open the door it is necessary to pull member 37 100 95 raising the plate 26 which disengages the latch 34 because of the connection 35 therebetween.

When it is desired to close the door 15 and move the hopper 19 the door 15 is 105 pushed against the wall 10. This causes the hopper 19 to be raised so that the lower ends of the stops 30 will clear the top of the stops 31, the hopper 19 when raised by the door being pushed against the wall 10 110 will be slightly inclined so that when the door 15 is lowered or as the door moves toward its closed position the hopper will clear the stops 31 and be pushed back into the chute and when the door is fully closed 115 the latch 32 will engage the catch 33 thus securing the door in closed position.

I do not limit myself to the exact details described but intend to cover such modifications and equivalent thereof as may properly come within the scope of my invention. Nor is my invention to be limited to a structure containing all of the devices described since obviously all of them are not interdependent although so related as to be used 120 and operated together. For example while I prefer to employ the protecting plate for the glazed section of the door it is obvious that with a heavy glass such plate is not 125 essential and may be omitted. Also I may 130

- employ a chain 27 that extends through a stop attached to the chute as 28 which chain will be properly movable therethrough. Also there may be a flexible connection between the hook latch 32 and the plate 26 so that the hook latch may be disengaged from the latch 33 when the chain 27 is pulled through the stop the plate will be raised sufficiently to disengage the hook latch from the catch. This results in the door 15 swinging outwardly as the hinged pivots are outwardly of the point of engagement between the hook and the latch thus permitting opening of the door when the latch is so disengaged.
- Having fully described my invention what I desire to cover by Letters Patent is:
1. In a device of the class described the combination of a casing, a glazed door hinged thereto, a chute slidably mounted in the casing arranged to lie wholly within the casing or to extend partially out of the casing, arms pivotally connected to the door and the chute for moving the chute by the opening or closing of the door, lugs carried by the lower portion of the door, a protecting plate pivoted thereto and arranged to overlie the glass in the door when the latter is opened and to extend along the bottom and lie within the chute when the door is closed, flexible means attached to the plate for urging it into protecting position substantially as described.
  2. In a device of the class described, the combination of a casing, a glazed door hinged thereto, a chute slidably mounted in the casing arranged to lie wholly within the casing or to extend partially out of the casing, arms pivotally connected to the door and the chute, for moving the chute by the opening or closing of the door, lugs carried by the lower portion of the door, a protecting plate pivoted thereto and arranged to overlie the glass in the door when the latter is opened and to extend along the bottom and lie within the chute when the door is closed and members mounted on the outer portion of the casing to guide the movement of the chute and adapted to engage the rear portion thereof when extended and hold it in extended position, substantially as described.
  3. In a coal chute, the combination of a chute, a door, a hopper, the latter being slidably mounted in the chute, arms pivotally connecting the door and the hopper, a glass in the door, lugs mounted on the lower portion of the door, a plate pivoted to said lugs independently movable with respect to said arms, and adapted to overlie the glass when the door is in raised position, said lugs being adapted to direct the plate into operative or inoperative position as the door is opened or closed, a flexible means attached to the plate for positively moving the same into protective position substantially as described.
  4. In a device of the class described, the combination of a chute, a door, a hopper, the latter being slidably mounted and adapted to lie wholly within the chute when the door is in closed position and to extend outwardly of the chute when the door is in raised position, arms pivotally connecting the door and the hopper, a glass in the door, a plate pivoted to the door and adapted to overlie the glass when the door is in raised position, and flexible means attached to the plate for holding the same over the said glass when the door is in opened position, substantially as described.
  5. In a device of the class described, the combination of a chute, a hopper, a door, arms connecting the door and the hopper, the hopper adapted to lie wholly within the chute when the door is in closed position, and to extend outwardly therefrom when the door is in open position, and guides on the outer portion of the chute adapted to guide the hopper when moved by the door and for abutting engagement with the rear portion of the hopper when the hopper is in outward position, substantially as described.
  6. In a device of the class described, the combination of a chute, a door, and a hopper, the latter being slidably mounted in the chute and adapted to lie wholly within the chute when the door is in closed position and to extend outwardly of the chute when the door is in open position, arms connecting the door and the hopper, a glass in the door, a plate pivoted to the inner portion of the door and adapted to overlie the glass when the door is in open position, means attached to the plate for holding the same against said glass and guides mounted on the chute for engagement with the hopper whereby the hopper is held against lateral bodily movement and is maintained in its outward position when the door is raised, and for directing the hopper inwardly when the door is moved to unlocking position, substantially as described.
  7. The combination of a chute, a hopper slidably mounted therein, a hinged door, operating arms connecting the door and the hopper, guide members on the chute for directing the inward and outward movement of the hopper and adapted to abut the rear portion of the chute when the latter is in outward position, substantially as described.
  8. In a device of the class described, the combination of a chute, a door and a hopper, the latter being slidably mounted in the chute and adapted to be wholly within the chute when the door is in closed position and to extend outwardly of the chute when the door is in open position, arms connect-

ing the door and the hopper, a glass in the door, a plate pivoted to the inner portion of the door and adapted to overlie the glass when the door is in open position, means attached to the plate for holding the same against said glass, a latch connected to said door, a flexible connection between said latch and said plate, whereby said latch is disengaged when said plate is raised, substantially as described.

9. In a device of the class described, the combination of a chute, a hopper, and a door having a transparent section, a movable protecting plate, means for operating

the hopper and the plate connected to the door, a latch connected to the door for engagement with the chute, a connection between said latch and said plate, and means connected to the plate for disconnecting the latch and holding the plate against said glass, substantially as described.

Signed at La Salle, in the county of La Salle, and State of Illinois, this 18th day of January, 1917.

WILLIAM V. HEINZ.

Correction in Letters Patent No. 1,286,618.

It is hereby certified that in Letters Patent No. 1,286,618, granted December 3, 1918, upon the application of William V. Heinz, of La Salle, Illinois, for an improvement in "Coal-Chutes," an error appears in the printed specification requiring correction as follows: Page 3, line 75, after the word "door" insert the words *lugs mounted on the door*; and that the said Letters Patent should be read with this correction therein that the same may conform to the record of the case in the Patent Office.

Signed and sealed this 21st day of January, A. D., 1919.

[SEAL.]

F. W. H. CLAY,

Acting Commissioner of Patents.

Cl. 193--33.
